MULTIPLE TUBING STRING PRODUCTION APPARATUS

Waldo W. Henslee, Jr., Houston, Tex., assignor to Baker Oil Tools, Inc., Los Angeles, Calif., a corporation of California

Filed Dec. 23, 1957, Ser. No. 704,649

5 Claims. (Cl. 166—243)

The present invention relates to subsurface well bore apparatus, and more particularly to apparatus for establishing individual communication between different formation zones in the well bore and a plurality of tubular strings extending to the top of the well bore.

An object of the present invention is to provide production apparatus capable of establishing communication between a plurality of formation zones in the well bore and more than two parallel tubular production strings disposed in the well bore and extending to the top thereof.

Another object of the invention is to provide production apparatus for conducting production individually from three different producing zones in a well bore through three separate parallel strings of production tubing to the top of the well bore.

A further object of the invention is to provide production apparatus for establishing communication between a plurality of formation zones in a well bore and three parallel tubular production strings disposed in the well bore, in which at least one of the tubular strings is lowered in the well bore and placed in proper assembled relation with the other apparatus in the well bore after such other apparatus has been disposed in its appropriate location in the well bore.

An additional object of the invention is to provide production apparatus for establishing communication between a plurality of formation zones in a well bore and three parallel tubular production strings disposed in the well bore, in which the third string can be run in the well bore and placed in proper relation to the other apparatus in the well bore after two other strings have been run simultaneously in the well bore.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figures 1 and 1a together constitute a longitudinal section through well apparatus disposed in a well casing, parts being shown in side elevation, Fig. 1a constituting a lower continuation of Fig. 1;

Fig. 2 is an enlarged longitudinal section through the apparatus disclosed in Fig. 1;

Fig. 3 is a cross-section taken along the line 3—3 on Fig. 2;

Fig. 4 is a side elevation of the track or guide portion of the apparatus.

In the specific form of apparatus shown in the drawings, it is desired to conduct well production from three longitudinally spaced formation producing zones individually through three strings of tubing 10, 11, 12 to the

2

top of the well bore. The production from the lowermost zone can pass into a well casing 13 through lower perforations 14, production from the intermediate zone can pass into the well casing through an intermediate set of perforations 15, and production from an upper zone can pass into the well casing through an upper set of casing perforations 16. The zones are separated by one another by suitable barrier devices. Thus, a lower packer 17 of any suitable type is anchored in packed-off condition in the well casing between the lower and intermediate sets of perforations 14, 15, an intermediate packer 18 is anchored in packed-off condition in the well casing between the intermediate and upper sets of perforations 15, 16 whereas an upper packer 19 is anchored in packed-off condition in the well casing above the upper set of perforations 16. These packers are shown diagrammatically in the drawings, and may be of the specific type shown in United States Patent Nos. 2,189,701, and 2,630,865. The three parallel strings of tubing 10, 11, 12 that are disposed in the well casing are related individually to receive production from one of the zones. Thus, the first string of tubing 10 is in communication with an inner tubing string 20 which extends through all packers to a location below the lower packer 17. This inner tubing string has suitable sealing devices or members 21 thereon adapted to seal against the wall of the passage 22 through the lower packer. This passage 22 has an smaller inside diameter than the passage 23 through the intermediate packer 18, whereas the passage through the intermediate packer has an inside diameter which is smaller than the passage 24 through the upper packer 19.

A second string of tubing 11 is adapted to receive production passing into the casing through the intermediate set of perforations 15. Communication is established between the second tubular string 11 and an intermediate tubing string 25 which surrounds the inner tubing string 20 and is spaced therefrom to provide an annular passage 26 for the flow of fluid. This intermediate tubing string 25 has suitable seal members 27 thereon adapted to sealingly engage the wall of the intermediate packer 18.

The third string of tubing 12 is adapted to receive production passing into the casing through the upper set of perforations 16. This third string of tubing is in communication with an upper tubular member or string 28 which surrounds the intermediate tubing string 25 and is in spaced relation therewith to provide an annular passage 29 for the flow of fluid. The upper tubing string 28 has suitable packing 30 thereon to make sealing engagement with the wall of the passage 24 through the upper packer. The lower end 31 of such upper tubular string is adapted to rest upon a shoulder 32 in the upper packer 19, so as to appropriately locate the seal members 27, 21 of the intermediate and lower tubing strings 25, 20 within their respective intermediate and lower packers 18, 17.

The first, second and third tubular strings 10, 11, 12, which extend to the top of the well bore, are placed in appropriate communication with the inner tubing string 20, the annulus 26 between the inner and intermediate tubular strings 20, 25, and the annulus 29 between the intermediate and upper tubing strings 25, 28 by means of a flow directing head 33 which is connected to the several tubular strings in a particular manner.

This head 33 has a lower threaded bore 34 threadedly receiving the upper end of the upper tubing string 28. It also has an intermediate threaded bore 35 coaxial with the lower threaded bore 34 for threadedly receiving the upper end of the intermediate tubing string 25, and it also has an upper threaded bore 36 coaxial with the other threaded bores for threadedly receiving the upper end of

the inner tubing string 20. The lower end of the first tubing string 10 is threaded into a box 37 in the upper portion of the head 33, and this threaded box communicates with a flow passage 38 communicating with the upper threaded bore 36, such that fluid can flow from the inner tubing string 20 into the passage 38 and thence into the first string of tubing 10 to the top of the well bore.

To one side of the threaded box 37 for the first string of tubing 10, the head 33 is provided with a second threaded box 39 into which the lower end of the second tubular string 11 is threaded, this threaded box opening downwardly into a passage 40 that opens into the annular space 41 between the upper portion of the inner tubular string 20 and an intermediate passage 42 in the head opening into the intermediate threaded bore 35, thus establishing communication between the annular space 26 between the inner and intermediate tubing strings 20, 25 and the second tubing string 11.

The third tubing string 12 is adapted to be disposed within a tubular receptacle 43, the lower end of which is threaded within a third threaded box 44 in the upper portion of the head 33, this threaded box communicating with a passage 45 extending downwardly through the head and opening into a lower passage 46 communicating with the lower threaded bore 34, so that fluid from the annulus 29 between the intermediate and upper tubing strings 25, 28 can flow through the head passages 46, 45 into the tubing receptacle 43, and thence into the third string of tubing 12. For convenience of manufacture, part of the passage 45 through the head 33 may be milled therein through the side wall of the head, the side of the passage being closed by a suitable plate 47 welded to the head and, in effect, constituting a part thereof. To prevent leakage of fluid between the third tubular string 12 and the receptacle 43, suitable side seals 48 are provided on the lower portion of the third string 12 for sealingly engaging the wall of the receptacle.

From the description which has been given above, it will be evident that production from the lower formation zone can flow through the lower set of perforations 14 into the casing 13, then proceeding upwardly through the inner tubular string 20 and the first flow passage 38 in the head 33 into the first tubular string 10, to be conducted to the top of the well bore. Production from the intermediate zone can pass through the intermediate casing perforations 15 to the interior of the casing, then flowing upwardly through the annulus 26 between the inner and intermediate tubing strings 20, 25 into the intermediate production flow passage 42 in the head 33, thence through the second passage 40 in the head and into the second string of tubing 11, to be conducted thereby to the top of the well bore. Production from the upper producing zone can pass through the upper casing perforations 16 into the well casing, flowing through the annulus 29 between the intermediate string 25 and upper packer 19, as well as this same annulus between the intermediate string and the upper tubing string 28 into the third head passage 46, 45, from where the production is carried through the tubing receptacle 43 into the third string of tubing 12 for conveyance to the top of the well bore. Since the well packers 17, 18, 19 isolate the producing zones from one another, the casing being cemented between the zones, and in view of the sealing relationship between the packing elements 21, 27, 30 on the inner, intermediate and upper tubing strings 20, 25, 28 with the lower, intermediate and upper packers, the well production is conducted separately from each producing zone through its own individual tubular string to the top of the well bore.

The apparatus illustrated is run in the well casing in a predetermined sequence. Thus, the lower packer 17 is run in the well casing 13 and anchored in packed-off condition therewithin between the lower and intermediate sets of perforations 14, 15. The intermediate packer 18 is then run in the well casing and anchored in packed-off condition therewithin between the intermediate and upper

sets of perforations 15, 16. The upper packer 19 is then run in the well casing and anchored in packed-off condition therewithin above the upper set of perforations 16. The locations of these packers are known, so that appropriate lengths of inner, intermediate and upper tubing strings 20, 25, 28 can be employed to secure a proper sealing relation between such tubing strings and the lower, intermediate and upper packers.

The upper end of the inner tubing string 20 is threaded within the upper threaded bore 36 of the flow directing head 33, this inner tubing string having its sealing members 21 mounted thereon. The intermediate tubing string 25, disposed over the inner tubing string 20, is threaded into the intermediate threaded bore 35 in the flow directing head 33, this intermediate tubing string also having its seal members 27 mounted thereon. The upper tubing string 28, which is disposed around the intermediate tubing string 25, is threaded into the lower threaded bore 34 in the head. The first tubular string 10 is then threaded into its companion bore 37 in the upper portion of the head, and the lower end of the second tubular string 11 is also threaded within its companion threaded bore 39. The tubing receptacle is threaded in its bore 44. This combination of apparatus with the first and second tubing strings 10, 11 threaded to the head 33 is then lowered in the well casing by means of additional stands or sections of first tubular string and second tubular string, which are coupled to the companion sections therewith until the inner, intermediate and upper tubing strings 20, 25, 28 are appropriately disposed within their respective well packers 17, 18, 19, as determined by engagement of the upper tubing string 28 with the shoulder 32 in the upper packer.

At this time, the seal members 21 of the inner tubing string 20 are sealingly engaging the wall of the lower packer passage 22; the seal members 27 of the intermediate tubing string 25 are sealingly engaging the wall of the intermediate packer passage 23; and the seal member 30 on the upper tubing string 28 is sealingly engaging the wall of the upper packer passage 24. The first tubular string 10 and the second tubular string 11 are thus appropriately related to the inner tubing string 20 and the annulus 26 between the inner and intermediate tubing string 20, 25, so that production from the lower zone can be conveyed into the first string 10 and production from the intermediate production zone into the second tubing string 11. At this time, however, the third tubing string 12 has not been disposed in the well bore, although its receptacle 43 has been threaded into the threaded box 44 in the upper portion of the head 33 preparatory to lowering of the apparatus in the well casing. After the apparatus has been lowered in the well casing and appropriately related to the packers therewithin, the third string of tubing 12 can be lowered in the well casing and is to be positively guided or steered into its receptacle 43. The structure for accomplishing this purpose will now be described.

By referring to Fig. 3, it will be noted that the threaded boxes 37, 39, 44 in the upper portion of the flow directing head 33 are not in line with one another, but are arranged in triangular fashion and rather closely clustered with respect to one another. The threaded box 37 for the first tubular string 10 may be disposed near the axis or center of the flow directing head, whereas the threaded box 39 for the second tubular string is disposed to one side of the threaded box 37 and toward the periphery of the head. The receptacle 43 which is to receive the third tubular string 12 is also disposed to one side and adjacent the threaded boxes 37, 39 for the first and second tubular strings 10, 11. From the foregoing arrangement, which is shown in Fig. 3, a substantial lateral space exists between the threaded box 37 for the first tubular string 10 and the periphery of the flow directing head 33, such space existing from the threaded box 39 of the second tubular string 11 in a counter-clockwise direc-

tion (as seen in Fig. 3) to the threaded box 44 for the third string receptacle 43. Similarly, a relatively short space exists in a clockwise direction between the threaded box 39 for the second tubular string 11 and the threaded box 44 for the receptacle 43. Track or guiding devices 50, 51 are disposed in these annular spaces so as to guide the third tubular string 12 into the receptacle 43 upon its lowering into the well casing 13.

As shown, one arcuate track member 50 extends between the threaded box 39 for the second tubular string 11 and past the threaded box 37 for the first tubular string 10 to the receptacle 43, its lower portion being suitably secured to the head 33 by welding. This track section 50 extends upwardly to a height above the upper end of the tubing receptacle 43, and is disposed laterally between the threaded box 37 for the first tubular string 10 and the periphery of the head 33. Its upper end 52 is tapered in a downward direction from a position adjacent the second tubular string 11 to a position adjacent the tubing receptacle 43 or the location of the third tubular string 12, and, in addition, this upper tapered end 52 of the track or guide is also beveled in an inward direction, as is shown most clearly in Fig. 4. Similarly, the relatively short track or guide section 51 is disposed between the threaded box 39 for the second tubular string 11 and the threaded box 44 for the receptacle 43 adjacent the periphery of the head 33. Its lower end is secured, as by welding, to the upper end of the head 33, and its upper end 53 extends above the upper end of the tubing receptacle 43. The upper end 53 of this guide tapers in a downward direction from the second string of tubing 11 to the location of the receptacle 43 or third tubular string 12, the lowermost end 54 of the taper, as well as the lowermost end 55 of the taper on the other track or guide section 50 being disposed above the upper end of the tubing receptacle 43. Here again, the upper end 53 of the short track or guide section is also beveled in an inward direction.

The parts are so proportioned and located that the third tubular string 12, when it is lowered down the well casing 13, will engage the upper end 52 of the larger track section 50 or the upper end 53 of the smaller track section 51. The distance between the first tubular string 10 and the large track section 50 is less than the diameter of the third tubular string 12, so that the third tubular string can never pass between the large track section 50 and the first tubular string 10, but must come to rest on the upper end 52 of the larger track section. Similarly, the distance between the larger track section 50 and the inner wall of the casing 13 is substantially less than the diameter of the third tubular string 12, so that it cannot pass between these parts. The same is true of the short track section 51, which, as shown, is disposed adjacent the periphery of the head 33. Accordingly, the third tubular string 12 can never move between the outside of the short section 51 and the wall of the well casing 13. If it is disposed above and in line with the short section 51, the third string will engage the upper end 53 of that section and will be guided thereby toward the receptacle 43, the upper end 56 of which is also beveled in an inward direction.

The apparatus is run in the well casing in the manner described above on the first and second strings of tubing 10, 11, the receptacle 43 having been previously threaded into its companion threaded box 44 in the flow directing head 33. After the apparatus has been appropriately related to the well packers, as shown in Figs. 1 and 1a, with the first and second tubing strings 10, 11 extending to the top of the well bore, the third tubing string 12 is lowered in the well casing 13. This third tubing string, when lowered to the guide members 50, 51, will engage either the upper end 53 of the small track section 51 or the upper end 52 of the large track section 50. Regardless of which one of these track sections it engages, it will be guided thereby toward the

tubing receptacle 43. If it engages the large track section 50, it will be guided down along its upper slope until it reaches its lowermost point 55, then dropping off the lowermost point into the tubing receptacle 43 and coming to rest against the shoulder 43a in the latter. If the lower end of the third tubular string 12 engages the upper end 53 of the short section 51, it will be guided toward its lowermost point 54, dropping off such lowermost point into the third receptacle 43. Both track sections are beveled in an inward direction so as to direct the tubing string 12 inwardly, and to its appropriate assembled relation within the third string receptacle 43. When received within the third string receptacle, the seals 48 on the lower portion of the third string 12 will sealingly engage the wall of the receptacle.

All three strings of tubing 10, 11, 12 are now appropriately connected to the flow directing head 13 and will conduct fluid from the lower, intermediate and upper zones of the well bore through individual paths to the top of the well bore.

The inventor claims:

1. In subsurface well production apparatus adapted for use with first, second and third tubular strings extending to the top of a well bore: a head adapted to be disposed in the well bore and having first, second and third passages therein; said head having first means in said first passage for receiving the first tubular string which extends to the top of the well bore; said head having second means in said second passage for receiving the second tubular string which extends to the top of the well bore; said head having a tubular receptacle in said third passage for receiving the third tubular string which extends to the top of the well bore; a first track section curved arcuately with respect to the axis of the head and secured to said head and extending arcuately in one direction from said second passage, past said first passage to said receptacle; said first track section having an upper end inclined in a downward direction from a location adjacent said second passage to a location adjacent said receptacle; a track section curved arcuately with respect to the axis of the head and secured to said head and extending arcuately in the opposite direction from said second passage to said receptacle, said second track section having an upper end inclined in a downward direction from a location adjacent said second passage to a location adjacent said receptacle; the lower ends of the inclined upper ends of said track sections terminating above the upper end of said receptacle, whereby engagement of either of said inclined upper ends by the third tubular string will direct the third tubular string into said receptacle.

2. In subsurface well production apparatus adapted for use with first, second and third tubular strings extending to the top of a well bore; a head adapted to be disposed in the well bore and having first, second and third passages therein; said head having first means in said first passage for receiving the first tubular string which extends to the top of the well bore; said head having second means in said second passage for receiving the second tubular string which extends to the top of the well bore; said head having third means in said third passage for receiving the third tubular string which extends to the top of the well bore; guide means on said head adapted to be engaged by the third string when it is lowered in the well bore to direct the third string into said third means; said head having a first threaded bore communicating with said first passage and adapted to receive an inner tubular string depending from the head; said head having an intermediate threaded bore communicating with said second passage and adapted to threadedly receive an intermediate tubing string surrounding the inner tubing string; said head having a threaded bore communicating with said third passage and adapted to receive an outer tubing string surrounding the intermediate tubing string.

3. In subsurface well production apparatus adapted for

use with first, second and third tubular strings extending to the top of a well bore; a head adapted to be disposed in the well bore and having first, second and third passages therein; said head having first means in said first passage for receiving the first tubular string which extends to the top of the well bore; said head having second means in said second passage for receiving the second tubular string which extends to the top of the well bore; said head having third means in said third passage for receiving the third tubular string which extends to the top of the well bore; and guide means on said head having an upper guide portion tapering downwardly toward said third passage from one of said other passages to said third passage, said guide portion being engageable by the third string to direct the third string from said one of said other passages into said third means; said head having a first threaded bore communicating with said first passage and adapted to receive an inner tubular string depending from the head; said head having an intermediate threaded bore communicating with said second passage and adapted to threadedly receive an intermediate tubing string surrounding the inner tubing string; said head having a threaded bore communicating with said third passage and adapted to receive an outer tubing string surrounding the intermediate tubing string.

4. In subsurface well production apparatus adapted for use with first, second and third tubular strings extending to the top of a well bore: a head adapted to be disposed in the well bore and having first, second and third passages therein; said head having first means in said first passage for receiving the first tubular string which extends to the top of the well bore; said head having second means in said second passage for receiving the second tubular string which extends to the top of the well bore; said head having third means in said third passage for receiving the third tubular string which extends to the top of the well bore; a first track section curved arcuately with respect to the axis of the head and secured to said head and extending arcuately in one direction from said second passage, past said first passage to said third passage, said first track section having an upper end inclined in a downward direction from a location adjacent said second passage to a location adjacent said third passage; a second track section curved arcuately with respect to the axis of the head and secured to said head and extending arcuately in the opposite direction from said second passage to said third passage, said second track section having an upper end inclined in a downward direction from a location adjacent said second passage to a location adjacent said third passage; said upper ends of said track sections being adapted to be engaged by the third string to direct the third string into said third means; said head having a first threaded bore communicating with said first passage and adapted to receive an inner tubular string depending from the head; said head having an intermediate threaded bore communicating with said second passage and adapted to threadedly receive an intermediate tubing string surrounding the inner tubing string; said head having a threaded bore communicating with said third passage and adapted to receive an outer tubing string surrounding the intermediate tubing string.

intermediate tubing string surrounding the inner tubing string; said head having a threaded bore communicating with said third passage and adapted to receive an outer tubing string surrounding the intermediate tubing string.

5. In subsurface well production apparatus adapted for use with first, second and third tubular strings extending to the top of a well bore: a head adapted to be disposed in the well bore and having first, second and third passages therein; said head having first means in said first passage for receiving the first tubular string which extends to the top of the well bore; said head having second means in said second passage for receiving the second tubular string which extends to the top of the well bore; said head having a tubular receptacle in said third passage for receiving the third tubular string which extends to the top of the well bore; a first track section curved arcuately with respect to the axis of the head and secured to said head and extending arcuately in one direction from said second passage, past said first passage to said receptacle; said first track section having an upper end inclined in a downward direction from a location adjacent said second passage to a location adjacent said receptacle; a second track section curved arcuately with respect to the axis of the head and secured to said head and extending arcuately in the opposite direction from said second passage to said receptacle, said second track section having an upper end inclined in a downward direction from a location adjacent said second passage to a location adjacent said receptacle; the lower ends of the inclined upper ends of said track sections terminating above the upper end of said receptacle, whereby engagement of either of said inclined upper ends by the third tubular string will direct said third tubular string into said receptacle; said head having a first threaded bore communicating with said first passage and adapted to receive an inner tubular string depending from the head; said head having an intermediate threaded bore communicating with said second passage and adapted to threadedly receive an intermediate tubing string surrounding the inner tubing string; said head having a threaded bore communicating with said third passage and adapted to receive an outer tubing string surrounding the intermediate tubing string.
